REFRIGERATOR DOOR

Clifford Brooks Stevens, Fox Point, and John Hughes, Jr.,
Whitefish Bay, Wis., assignors to Gibson Refrigerator
Company, Greenville, Mich., a corporation of Michigan

Application May 6, 1955, Serial No. 35,869

Term of patent 3½ years

(Cl. D67—3)

Fig. 1 is a perspective view of a refrigerator door showing our new design;

Fig. 2 is a perspective view of the other side of the door shown in Fig. 1;

Fig. 3 is a top plan view;

Fig. 4 is a side view in elevation;

Fig. 5 is an enlarged detailed sectional view, the section being taken as indicated at line 5—5 of Fig. 3, and

Fig. 6 is an enlarged sectional view, the section being taken as indicated at line 6—6 of Fig. 4.

We claim:
The ornamental design for a refrigerator door, as shown.
